UNITED STATES PATENT OFFICE.

WILLIAM ILE, OF JACKSON, MICHIGAN, ASSIGNOR TO REYNOLDS SPRING COMPANY, OF JACKSON, MICHIGAN, A CORPORATION OF DELAWARE.

CORD CONNECTER.

Application filed May 6, 1926. Serial No. 107,284.

The invention relates to a cord connector.

The object of the present invention is to provide a simple, practical and efficient cord connector of strong, durable and comparatively inexpensive construction, designed for connecting the cord leading from an outlet to a lamp or other electrical appliance and capable of enabling the cord to be readily disconnected without detaching the same from the outlet.

A further object of the invention is to provide a cord connector of this character composed of separable sections adapted to be readily connected and disconnected at a point distant from the outlet and capable of effectually preventing the contacts of the section connected with the cord leading from the outlet from coming in contact with the hands or other portion of a person, thereby effectually protecting the latter from shocks in assembling the sections of the cord connector and separating them.

Another object of the invention is to provide a cord connector of this character which when necessary will afford ready access to its contacts for the attachment or removal of the cord.

With these and other objects in view, the invention consists in the construction and novel combination of parts hereinafter described, illustrated in the accompanying drawings, and pointed out in the claims hereto appended, it being understood that various changes in the form, proportion and minor details of construction, within the scope of the claims, may be resorted to without departing from the spirit or sacrificing any of the advantages of the invention.

In the drawings:

Fig. 1 is a side elevation of a cord connector constructed in accordance with this invention;

Fig. 2 is a longitudinal sectional view of the same;

Fig. 3 is a plan view of the cap section having the knife contacts showing the inner face of the cap section, the insulating disk being removed;

Fig. 4 is a plan view of the insulating disk;

Fig. 5 is a plan view of the cap section having the spring contacts;

Fig. 6 is a detailed perspective view of one of the conductor plates;

Fig. 7 is a detailed perspective view of one of the spring contacts;

Fig. 8 is a plan view of the intermediate section showing the outer face thereof;

Fig. 9 is a similar view showing the inner face thereof;

Fig. 10 is a detailed perspective view of one of the curved corrugated fingers;

Fig. 11 is a detailed sectional view illustrating the manner of securing the curved fingers to the intermediate section.

In the accompanying drawings in which is illustrated the preferred embodiment of the invention, the cord connector comprises in its construction cap sections 1 and 2 and an intermediate cylindrical section 3, each

section being constructed of a single piece of molded insulating material, such as bakelite. The cap sections 1 and 2, which are approximately semi-spherical, are of sub-

stantially the same construction and are provided with central openings 4 and 5 for the introduction of the portions 6 and 7 of

the cord to be connected. The cap section 1 constitutes a separable member and is provided with knife contacts 8 which are

adapted to engage spring contacts 9. The knife contacts 8 are formed integral with attaching plates 10 secured by tubular rivets

11 to the cap section 1 in suitable recesses 12 thereof, the recesses forming the seats for

the attaching portions of the knife contacts. The tubular rivets are embedded in the material of the cap section and the plates are

provided at one end with lugs 13 for interlocking the plates with the end section. The

wires of the portion 6 of the cord are secured to the plates of the knife contacts by binding

screws 14 mounted on the plates 10 at the opposite end to that having the lugs 13.

The inner face of the end section is normally covered by an insulating disk 15 provided

with slots 16 to receive the knife contacts, and having curved radial recesses 17 at op-

posite sides of its periphery to clear the portions 18 of the end cap. This will per-

mit the insulating disk to fit snugly within the end cap and will cover and conceal the

terminals of the wires of the cord 6. The cord 6 is designed to be connected with the

lamp or other appliance, while the cord 7 is designed to extend to a floor plug or other

outlet.

The cap section 2 is provided with seats

19 to receive combined conductor and attachment plates 20 provided with upwardly extending transversely disposed lugs 21 which have recesses 22 to be engaged by 5 curved corrugated fingers 23 of the intermediate section. The plates 20 are secured to the section 2 by tubular rivets 24 which are embedded in the material of the end section and which also pass through arms 10 25 of the spring contacts. The spring contacts which are approximately U-shaped, are provided with the said arms 25, which form an extension of one side of the spring contacts. The arm is interposed between 15 the plates and the seats of the end section and the rivets 24 pierce both the plates 20 and the arms 25. The spring contacts are arranged at right angles to the lugs 21 and the recesses are located at the outer side 20 edges of the lugs adjacent to the marginal flange or portion of the end cap. The terminals of the wire of the cord 7 are secured to the plates 20 by binding screws 26 and the said cord is designed to extend to an 25 outlet or fixture and is not removed therefrom when the sections of the cord connector are separated.

The intermediate section 3, which is cylindrical, is provided with a peripheral recess forming a reduced annular flange 27 which fits within the marginal flange of the cap section 2. The said intermediate section is provided at its inner face at opposite sides with curved recesses 28 to receive the 30 curved fingers which are provided with attaching flanges or portions 29 secured by tubular rivets 30 to the intermediate section. The rivets are embedded in the material 35 of the end section and do not extend to the outer face thereof, so that the cap section 2 is effectively closed and its contacts prevented from coming into contact with a person handling the device. The intermediate 40 section is provided with spaced slots 31 for the passage of the knife contacts, and it is assembled by placing it on the section 2 and partially rotating it to carry its curved corrugated fingers into the recesses of the lugs 21. This partial rotary movement also 45 carries the slots 31 to their proper position adjacent the spring contacts, and when the knife contacts are passed through the slots 31 the spring contacts are partially compressed and a perfect electrical connection or engagement is effected. At the 50 same time the knife contacts lock the intermediate section against rotary movement by engaging with the lugs 21 which form stops and hold the knife contacts against rotary 55 movement. When the plug section formed by the cap section 1 and the knife contacts is assembled and connected with the other sections, there is no liability of the intermediate section having any relative rotary 60 movement and it will be impossible for the 65

intermediate section to become accidentally disengaged from the section 2 which carries the spring contacts and which is connected with the outlet box or fixture.

What is claimed is:

1. A cord connector comprising cap sections and an intermediate section, said sections being constructed of molded insulating material, spring contacts carried by one of the cap sections, knife contacts mounted 75 on the other cap section and adapted to engage the spring contacts, cooperating means carried by the intermediate section and the cap section having the spring contacts and interlocking the intermediate section with 80 such cap section and movable into and out of engagement by a relative rotary movement of the cap and intermediate sections, said intermediate section being provided with slots through which pass the knife 85 contacts, whereby the intermediate section is held against relative rotary movement and is retained in its interlocked relation with the cap section when the knife contacts are in engagement with the spring contacts and the parts assembled. 90

2. A cord connector comprising a cap section, spring contacts carried by the cap section, lugs arranged adjacent the spring contacts and having engaging portions, an intermediate section fitted on the said cap section at the inner face thereof and forming 95 a cover for the same for protecting the spring contacts, fingers mounted within the intermediate section and adapted to be carried by a rotary movement into and out of engagement with the said lugs, and a cap section fitted on the intermediate section and provided with knife contacts extending through the intermediate section and 100 engaging the spring contacts and also locking the intermediate section against rotary movement. 105

3. A cord connector comprising a cap section, combined conductor and attachment 110 plates secured to the cap section and provided with means for the attachment of wires and having lugs provided with recesses, spring contacts arranged adjacent to the lugs and having portions secured to the cap section by the said plates, a cylindrical intermediate section fitted on the cap section and covering the spring contacts thereof and provided with means adapted to be carried into and out of engagement with the said lugs by partial rotary movement of the intermediate section, and a cap section provided with knife contacts extending through the intermediate section and engaging the spring contacts and locking the intermediate section against 115 rotary movement. 120

4. A cord connector comprising a cap section, combined conductor and attachment plates secured to the cap section and pro- 125

vided with means for the attachment of wires and having lugs provided with recesses, spring contacts arranged adjacent to the lugs and having arms extending beneath the said plates and secured to the cap section, a cylindrical intermediate section fitted on the cap section and covering the contacts thereof and provided with curved fingers arranged to be carried into and out of engagement with the lugs by the partial rotary movement of the intermediate section and having attaching portions secured to the same, and a cap section fitted on the intermediate section and provided with knife contacts extending through the intermediate section and engaging the spring contacts and held against rotary movement by the said lugs.

5. A cord connector comprising a cap section, combined conductor and attachment plates secured to the cap section and provided with means for the attachment of wires and having lugs provided with recesses, spring contacts arranged adjacent to the lugs and having arms extending beneath the said plates and secured to the cap section, a cylindrical intermediate section having an annular flange, said intermediate

section being provided with inner recesses and having slots located at the recesses, 30 fingers mounted in the recesses and arranged to be carried into and out of engagement with the lugs by partial rotary movement of the intermediate section, and a cap section having knife contacts extending through 35 the slots of the intermediate section and engaging the lugs and the spring contacts.

6. A cord connector comprising an end section having spring contacts, an intermediate cylindrical section covering the 40 spring contacts and secured to the cap section, a cap section provided with seats and having inwardly extending portions adjacent the seats, knife contacts secured on the said seats and extending through the intermediate 45 section and engaging the spring contacts, and an insulating disk having slots to receive the knife contacts and provided with radial recesses for engaging the said inwardly extending portions of the cap section 50 and fitting within the same to cover the wire attaching means.

In testimony whereof I have hereunto set my hand.

WILLIAM ILE.
